UNITED STATES PATENT OFFICE.

GILBERT JACKSON, OF NEW YORK, N. Y.

BOTTLE-VALVE.

1,348,116.

Specification of Letters Patent. Patented July 27, 1920.

Application filed December 6, 1916, Serial No. 135,343. Renewed February 1, 1919. Serial No. 274,566.

To all whom it may concern:

Be it known that I, GILBERT JACKSON, a citizen of the United States, residing at New York, in the borough of Manhattan, 5 city of New York, and State of New York, have invented certain new and useful Improvements in Bottle-Valves, of which the following is a specification.

My invention relates to bottle valves, and 10 more particularly that class which has for its object to prevent the refilling of bottles after they have been once emptied, and contemplates certain improvements in the construction of the same, as will be more definitely pointed out and claimed hereinafter, 15 reference being had to the accompanying drawings, in which:—

Figure 1 is a central vertical sectional view of my improved device located in a bottle 20 neck.

Fig. 2 is a transverse section, taken on the line II—II of Fig. 1.

Fig. 3 is a view of the various parts of the bottle valve, shown separated and in 25 perspective.

Fig. 4 is a vertical sectional view of a modified form of the bottle valve.

Similar numerals of reference denote corresponding parts in the several views.

30 In the said drawing, the reference numeral 1 denotes the neck of an ordinary bottle, such as a whisky bottle, in which is disposed a partial closure 2 forming a valve seat 3, upon which is adapted to seat the

35 lower curved end 4 of a hollow valve member 5, said valve seat and valve member being formed of some porous material of a character which will cause said valve and seat, when the parts are wet, to stick to each

40 other against relative movement when the bottle is shaken, and yet will permit said valve to leave its seat when the bottle is inverted and the pressure of the liquid is exerted thereon. The valve member 5 is closed

45 at its upper end, preferably by a cork piece 6, into a central aperture in which fits the stem 7 of a disk 8, which is of even diameter with the exterior diameter of the valve member 5, and is for a purpose hereinafter

50 to be described. Fitted to the top of the partial closure 2 is a casing 9, of porcelain, or other suitable material, provided with a discharge orifice 10, and below said orifice being enlarged interiorly to correspond with 55 the interior diameter of the upper end of the partial closure 2, the interior of the

upper end of the casing 9 being screw-threaded at 11 to receive similar screw-threads 12 on a plug 13 screwed thereinto, the screw-threaded portion of said plug 60 being mutilated at intervals longitudinally at 14 to provide liquid passages therearound, the upper end of said plug being formed with projections 15 spacing it from the upper interior wall of the casing, whereby 65 a free passage of liquid in the bottle is permitted therearound. Interposed between the top of the valve member 5 and the lower concaved surface 16 of the plug 13 is a ball 17 of glass or other suitable material, an ap- 70 preciable space being left between the two when the ball is resting upon the cap 8, said construction, when the bottle is inverted, permitting the valve member 5, when the ball 17 drops into the cup-shaped portion 75 16 of the plug 13, to leave its seat 3 and permit the flow of liquid from the interior of the bottle past the same.

In operation, with the bottle in the vertical position shown in Fig. 1, the ball 17 80 rests upon the valve member 5 and aids in maintaining it in its closed position, but when the bottle is inverted the ball 17 drops into the seat 16, thus releasing the valve 5 and permitting the flow of liquid 85 past the same, and, through the recesses 14 of the plug 13, to the discharge opening 10 of the casing 9, said valve member being spaced from the inner wall of the partial closure 2 by the ribs or fins 18. Under or- 90 dinary circumstances this construction most effectually will prevent the refilling of the bottle through the pouring of liquid in the neck 10, when the bottle is in the vertical position. Nor will it be possible to cause 95 the liquid to flow into the bottle by agitating the bottle vertically, as the semi-porous character of the partial closure 2 and valve member 5 will cause the latter to stick suffi- 100 ciently to its seat 3 to prevent any move- 105 ment of the valve away from its seat under vertical agitation of the bottle, and yet will not be sufficient to cause said valve to remain seated when the pressure of liquid in the bottle comes against it as the bottle is inverted.

In order to prevent a refilling of the bot- 110 tle by subjecting the same to a vacuum, which is a well known test of this type of bottle valves, the disk 8 is provided. In operation, when said disk and its stem 7 are forced through the cork piece 6 the air

in the interior chamber of the valve member 5 necessarily is confined. Now, when the bottle is subjected to a vacuum in a closed chamber, the differential of pressure 5 created thereby will cause the stem 7 to be forced out of the cork piece 6, whereby the ball 17 will be forced against its seat 16, thereby retaining the valve member 5 firmly against its seat, and preventing any ingress 10 of liquid into the bottle, and said disk 8 will remain in its projected position, effectually preventing any refilling until the members of the bottle valve are separated in dismantling the structure.

15 I have shown in Fig. 4 a slightly modified construction, wherein the disk 8 is dispensed with, the solid cork piece 19 operating in the same manner as does the disk 8 when the bottle is subjected to a vacuum, and 20 forcing the ball 17 against its seat 16.

While I contemplate employing any semi-porous material from which to form the partial closure 2 and the valve member 5, still I have found that a magnesium compound 25 constitutes the most advantageous material in that not only does it possess the necessary porosity, but also is of a weight light enough properly to function as the valve member.

30 The valve seat 3 being of porous material will permit air to pass through the same, thus preventing a vacuum from being formed in the bottle due to the expansion and contraction of its contents under variations 35 of temperature.

The material of which I make the lower end 4 of the valve member 5 and the partial closure 2 forming the valve seat 3 may be any semi-porous substance, such as unglazed 40 pottery of any description, though I prefer to employ a substance known in the trade as "magnesia ware" now sold in the open market, the base of the same being magnesium, but which is understood to be manufactured under a secret process.

Having thus described my invention, what I claim as new and desire to secure by Letters Patent, is:—

1. A bottle valve, comprising a valve seat,

a valve therefor having a broad area of 50 contact therewith, said valve and seat being formed of semi-porous material of a character which when wetted will stick against movement under vibratory agitation of the bottle.

2. A bottle valve, comprising a valve seat, a valve therefor, and a retainer for holding said valve on its seat and having limited movement, said valve being adapted to lengthen when subjected to a vacuum to fill 60 the space and prevent the valve from leaving its seat.

3. A bottle valve, comprising a valve seat, a valve therefor, a retainer for holding said valve on its seat and having limited movement, and a movable element in said valve adapted when subjected to a vacuum to move toward said retainer to wedge the latter in position, thereby preventing said valve from leaving its seat.

4. A bottle valve, comprising a valve seat, a hollow valve therefor, a retainer for holding said valve on its seat and having limited movement, and a plug in said hollow valve upon which said retainer rests, said 75 plug adapted when seated to cause a retention of air within said hollow valve, whereby when said valve is subjected to a vacuum said retained air will force out said plug against said retainer and thereby lock 80 the parts with the valve in its closed position.

5. The combination with a bottle; of a stopper disposed in the neck thereof and a pneumatically controlled valve in said stopper to prevent unauthorized refilling of the bottle.

6. The combination with a bottle; of a stopper disposed in the neck thereof, a valve member movable in said stopper and having a fluid chamber therein, a pneumatically controlled plunger slidably in said chamber, and means between said plunger and stopper to hold said valve normally closed.

In testimony whereof, I hereunto set my hand this 5th day of December, 1916.

GILBERT JACKSON.
